UNITED STATES PATENT OFFICE.

MAURICE HENDBERG, OF BOSTON, MASSACHUSETTS.

DESIGN FOR JEWELRY-CASES.

Specification forming part of Design No. **6,540**, dated April 1, 1873; application filed March 10, 1873.

To all whom it may concern:

Be it known that I, MAURICE HENDBERG, of Boston, in the county of Suffolk and State of Massachusetts, have invented a new and original Design for Jewel-Cases; and I do hereby declare the following to be a full, clear, and exact description of the invention, such as will enable others skilled in the art to which it pertains to make and use it, reference being had to the accompanying drawing which forms part of this specification.

My invention relates to a new design for jewel-cases, and is fully represented in the drawing, on which Figure 1 is a perspective outside view. Fig. 2 is a perspective view of the lower part, and Fig. 3 is a perspective view of the cover.

The design consists in making a jewel-case

representing a miniature helmet, and having a suitable ornamentation in front, such as a star, or otherwise, as shown in Fig. 1. Fig. 2 shows the case or box proper intended to contain the ring or other jewelry, and Fig. 3 represents the cover. The whole when put together appears as a helmet, shown in Fig. 1.

Having thus described my invention, I wish to secure by Letters Patent and claim—

The new and original design for a jewel-case, as herein shown, and represented in the drawing.

In testimony that I claim the foregoing I have hereunto set my hand this 4th day of March, 1873.

Witnesses: MAURICE HENDBERG,
ALBEN ANDRÉN,
JOHN R. HEARD.
